UNITED STATES PATENT OFFICE.

WILLARD F. MILLS, OF KALAMAZOO, MICHIGAN.

MACHINE FOR BENDING METAL SASH.

SPECIFICATION forming part of Letters Patent No. 399,683, dated March 19, 1889.

Application filed June 12, 1888. Serial No. 276,840. (No model.)

To all whom it may concern:

Be it known that I, WILLARD F. MILLS, a citizen of the United States, residing at Kalamazoo, county of Kalamazoo, State of Michigan, have invented a new and useful Machine for Bending Metal Sash, of which the following is a specification.

This invention has for its object the construction of a machine for bending in curved and circular form I-shaped metal sash for sectional glass-work, substantially as below described and claimed.

In the drawings forming a part of this specification, Figure 1 is a side elevation; Fig. 2, an end elevation looking from a point at left of Fig. 1; Figs. 3 and 4, enlarged details of a portion of the machine.

Referring to the lettered parts of the drawings, A is a frame, to the block C of which a jaw, B, is attached. This jaw has a convexed end, as at S, Figs. 2 and 3. To this jaw B is pivoted at z a jaw, D, having a concaved end—that is, the meeting ends of the jaws or the lips of the jaws are on a curve. The I-shaped sash I is placed between these jaws, and by moving up and down the handle of the jaw D and pushing the sash along through the jaws it is bent in circular form, as indicated by the curved part in dotted

30 lines in Fig. 3. The more firmly the jaws are set together the smaller the circle of the sash will be, and to this end, that the circle shall be of the desired size, an adjustable stop, u, is employed, which, in connection

35 with the shoulders on the jaws of the device, where they are pivoted, limits the movement of the jaw D. The stop u is a screw screwed into the frame, and can be raised or lowered. In some instances the stop can be dispensed

40 with, provided the operator is sufficiently

skillful to govern the pressure on the jaws.

To prevent the sash from puckering I, employ a clamp which presses against each headed or flanged side of the sash. (See a x 45 in Fig. 4.) The clamp consists of a lever, x, pivoted to the frame A at the top, and a lever, a, pivoted to the fixed jaw B at 2, or to other suitable support. This clamp may be operated by any suitable means. For con-

venience I have arranged to operate the clamp 50 with the foot. At v b is a vertical rod attached at the upper end to the end of the lever a. A rod, f, is pivotally attached to the end of rod v b and to the treadle P. Toggle e e' connects the lever x of the clamp with 55 the vertically-playing rod v b; or, rather, the part e of the toggle connects pivotally with said parts, and the part e' is pivoted to the vertically-playing rod at one end and is pivoted to the frame at the other end, or, as 60 here shown, to a projecting bracket from the frame. The rod is carried down against the resistance of spring s', which spring is attached to the top of the frame A or table and to said rod. Thus the operator in bending 65 the sash I, Figs. 3 and 4, from a straight to a curved or circular form inserts the sash between the jaws, sets the clamp by pressing his foot on the treadle P, and closes the jaws by bearing down on the handled end of jaw 70 D. The clamp and jaws are then released, the sash pushed in a little farther, and the clamp and jaws brought to bear against the sash again, and so on the operation is continued.

Having thus described the invention, what I claim is—

1. The combination of a suitable frame or support, jaws pivoted to open and close and having their gripping ends curved, a clamp 80 for clamping the sash on each flanged side, and means for operating said clamp, substantially as set forth.

2. The combination of a suitable support, the jaws having their gripping ends curved, 85 said jaws mounted upon said supports, one of the jaws being pivoted to the other, the latter being stationary, a clamp on each side of the jaws for clamping the flanged sides of the sash, and an adjustable stop to limit the 90 play of the movable jaw, substantially as set forth.

3. The combination of a suitable support, the jaws having the curved ends, the pivoted clamp-levers arranged to clamp the sash 95 in the jaws between them, the vertically-playing rod attached to the end of one of the clamp-levers, a treadle to which the other

end is attached, a spring forming a resistance to the downward movement of said rod, a toggle-bar pivoted to the end of the other clamp-lever and to the vertically-playing rod, and a toggle-bar pivoted to said rod at one end and to a suitable support at the other end, substantially as set forth.

In testimony of the foregoing I have hereunto subscribed my name in presence of two witnesses.

WILLARD F. MILLS.
